COMBINED CART AND COOKING APPARATUS

Walter Koziol, Russell, Ill., assignor to Charmglow
Manufacturing Co., Antioch, Ill., a corporation of Illinois

Filed June 30, 1969, Ser. No. 17,972

Term of patent 14 years

Int. Cl. D7—04

U.S. Cl. D81—10

FIG.1

FIG.7

FIG.8

FIG. 1 is a perspective view of a combined cart and cooking apparatus showing my design;

FIG. 2 is an end view in elevation of the cart and cooking apparatus shown in FIG. 1;

FIG. 3 is a front view in elevation of the cart and cooking apparatus illustrated in FIG. 1;

FIG. 4 is a back view in elevation of the combined cart and cooking apparatus;

FIG. 5 is a perspective view of a modified form of a combined cart and cooking apparatus;

FIG. 6 is an end view in elevation of the unit shown in FIG. 5;

FIG. 7 is a front view in elevation of the cart and cooking apparatus illustrated in FIG. 5; and

FIG. 8 is a back view in elevation of the combined cart and cooking apparatus.

The broken line showing of wheels in all of the figures, the panels and indentations in all of the figures and a handle in FIGS. 1, 2, 3, 5, 6 and 7 is for illustration only.

I claim:

The ornamental design of a combined cart and cooking apparatus, substantially as shown and described.
